US0D1092701S

(12) **United States Design Patent** (10) **Patent No.:** **US D1,092,701 S**
(45) **Date of Patent:** **** Sep. 9, 2025**

(54) **DEHUMIDIFIER**

(71) Applicant: **LG ELECTRONICS INC.**, Seoul (KR)

(72) Inventors: **Heejae Kwon**, Seoul (KR); **Seungho Baek**, Seoul (KR); **Jeeyoung Yeon**, Seoul (KR)

(73) Assignee: **LG ELECTRONICS INC.**, Seoul (KR)

(**) Term: **15 Years**

(21) Appl. No.: **35/522,753**

(22) Filed: **Oct. 24, 2023**

(80) **Hague Agreement Data**

Int. Filing Date: **Oct. 24, 2023**

Int. Reg. No.: **DM/233084**

Int. Reg. Date: **Oct. 24, 2023**

Int. Reg. Pub. Date: **Oct. 25, 2024**

(30) **Foreign Application Priority Data**

May 8, 2023 (KR) 30-2023-0017394

(51) **LOC (15) Cl.** **23-04**

(52) **U.S. Cl.**

USPC **D23/359**

(58) **Field of Classification Search**

USPC D23/314, 355–356, 359–360, 362, 364,

D23/366

CPC F24F 3/14; F24F 2003/144
